No. 13.353

Oct 24, 1882

UNITED STATES PATENT OFFICE.

JOHN GLEN, OF BROOKLYN, NEW YORK.

DESIGN FOR A PRINTED FABRIC.

SPECIFICATION forming part of Design No. 13,353, dated October 24, 1882.

Application filed September 26, 1882. Term of patent 3½ years.

To all whom it may concern:

Be it known that I, JOHN GLEN, of Brooklyn, Kings county, in the State of New York, have invented a new and original Design for

5 Printed Fabrics; and I do hereby declare that the following specification, taken in connection with the accompanying illustration, forming a part of the same, is a full, clear, and exact description thereof.

10 My design relates particularly to printed fabrics known as "calicoes," although it is equally applicable to silks, woolens, and other fabrics, either printed or woven.

15 It consists in the representation of flowering vines, as will hereinafter appear.

Referring to the illustration, A A represent flowers upon a trailing vine, *a*, and B B repre-

sent flowers upon a trailing vine, *b*. Each of the vines *a* *b* also bears smaller flowers and leaves. The vines and flowers are repeated upon the 20 ground of the fabric to form the pattern.

The fabric may be produced in any preferred variety or combination of colors for giving a desirable effect to the design.

What I claim, and desire to secure by Letters Patent, is—

The design for printed and other fabrics, consisting of trailing vines *a* *b*, bearing flowers A A and B B, respectively, substantially as described and shown.

JOHN GLEN.

Witnesses:

JOHN G. DATER,
CHAS. G. TODD.
